YERVANT H. KURKJIAN, OF HAWTHORNE, NEW JERSEY, ASSIGNOR TO CARL J. SCHMID, INC., OF NEW YORK, N. Y., A CORPORATION OF NEW YORK

BEAD FORMING DEVICE

Application filed March 7, 1930. Serial No. 434,153.

My invention relates to bead forming devices and refers particularly to devices adapted for forming beads upon the open ends of rubber articles such as balloons, finger cots and similar devices.

Rubber articles of the character mentioned are generally produced by depositing a thin film of rubber upon a form, usually of glass, of the general shape of the desired article, 10 forming a bead around the open end of the device by rolling the lower edge thereof while the unvulcanized article is upon the form, vulcanizing and then removing the article from the form.

15 During the bead forming operation, the rubber is soft, sticky and weak and adheres to the form with considerable tenacity and therefore the greatest care must be exercised during this period of production.

20 The object of the bead is to strengthen the device and to prevent its being torn during use and hence it is essential that it be absolutely uniform throughout.

If the bead when formed has spots of 25 less thickness than others, or if it has balls, or "knots", that is an accumulation of rubber in one spot, it is so weakened that it is practically useless and hence must be discarded.

Because of the thinness and sticky nature 30 of the material and because of its liability to be torn, great difficulty has been experienced in avoiding the production of useless and imperfect devices.

The most satisfactory results are obtained 35 by producing the articles upon revoluble forms, and then submitting these revolving forms to the action of an inclined revolving brush adapted to gradually and uniformly roll the edge to form a bead.

40 It is evident that a proper relationship of revolution between the forms and the brushes must be obtained in order that the bead will not be formed too rapidly or too slowly and that this relationship must be maintained without change or interruption.

In the application of this process of bead forming, the revolving brushes are inclined 45 with respect to a table, and the revolving forms are passed across the table in proper abutment with the brushes. There is, there-

fore, a revoluble and a horizontal movement of the forms against the brushes of the revolving inclined brushes. Hence it is necessary that these three movements be in proper synchronization with each other in 55 order to produce a uniform bead.

Assuming the revolution of the brush to be uniform, it is evident that if the horizontal movement or the revolution of a form be decreased from normal movement or speed of revolution, the brush will act for a longer 60 period of time upon one spot of the device thus causing an accumulation of rubber at that point, forming a "knot" and the bead will not be uniform.

Upon the other hand, if the horizontal movement or the revolution of a form be increased from normal movement or speed of revolution the brush will act for a shorter 65 period of time upon one spot of the device thus causing a deficiency of rubber at that point and producing a uniform bead.

70 The object of my invention is a device which will overcome the above mentioned and other objectionable features of the 75 present known device, and which will produce a uniform bead upon rubber articles of the character described.

In the accompanying drawings illustrating 80 one form of the device of my invention, similar parts are designated by similar numerals.

Figure 1 is a top view of one form of the device of my invention.

Figure 2 is a section on line 2—2 of Fig- 85 ure 1.

Figure 3 is a section on line 3—3 of Fig- 90 ure 1.

Figure 4 is an enlarged fragmentary view of a portion of the rack sections partly bro- 95 ken away for clearness of description.

Figure 5 is a section on line 5—5 of Fig- 90 ure 4.

Figure 6 is a section on line 6—6 of Fig- 95 ure 7.

Figure 7 is a section on line 7—7 of Fig- 100 ure 6.

The particular form of the device of my invention illustrated in the accompanying drawings comprises a table 10 supported by

legs 11, 11, portion 12, 12' of the table 10 being cut away and a plurality of idlers 13, 13' being positioned transversely within these cut out portions.

5 A revoluble brush carrying shaft 14 is revoluble in the bearings 15, 15 carried by the supports 16, 16. Each support 16 has a vertical slot 17, a set-bolt 18 passing through said slot and through and opening in the support 16, the latter being fixedly attached to the table 10. By these means the brush 20 may be raised and lowered to any desired position. It is to be noted that the axis of the brush 20 is positioned angularly to the 15 top of the table 10.

The device contains a revoluble brush 20' which is supported and arranged as the brush 20, the several corresponding parts being designated by corresponding prime numerals.

20 Positioned upon the table 10 are two parallel spaced rack-carrying members 21 and 21'. Plates 22 and 22' are positioned between the rack-carrying members 21 and 21' and the supports 23 and 23'.

25 The rack-carrying members 21 and 21' have a plurality of recesses 24, 24 arranged in pairs. Each of a plurality of racks 25, 25 carries a pair of rods 26, 26 which pass through the recesses 24, 24 and through an opening in the rear wall of a member 21 and are fixed therein by means of a cotter-pin 27. A coil spring 28 is positioned within each recess 24 and abuts upon a rack 25 and the rear wall of the recess, thus having a normal tendency to force the rack outwardly. The plates 29 and 22 act as guides for the 35 racks.

There is thus formed a run-way, the two 40 sides of which consist of a plurality of spring controlled horizontally movable rack sections forming a continuous rack.

Beneath the racks 25, 25 and above the table 10 is a movable conveyor belt comprising a plurality of links 30, 30, every alternate link having an inwardly extended carrier 31. The chain belt passes over the revoluble sprockets 32 and 33.

A similar conveyor belt is similarly positioned upon the other side of the run-way 50 as indicated with prime numerals.

In order to keep the belts pressed inwardly of the run-way to co-act with a platform, described later, a plurality of links 34, 34 are pivotally attached to the table 10. Each 55 link 34 carries a sprocket 35 capable of co-acting with the links of the conveyor chain. A spiral spring 36 has a tendency to move each sprocket 35 toward the conveyor chain, thus pressing the latter inwardly toward the 60 run-way.

The operation of the device is as follows:—

The drive shaft 37 is revolved thus revolving the sprocket 38 and the gear 39. A chain belt 40 meshes with the sprocket 38 and a sprocket 41 carried by the shaft 14 thus re-

volving the brush 20'. The gear 42 carried by the revoluble shaft 51 meshes with gear 39 and the sprocket 52 is connected by means of the chain belt 43 with the sprocket 44 carried by the revoluble shaft 45 which also carries the sprocket 46. A chain belt 47 connects the sprocket 46 with the sprocket 48 carried by the shaft 14, thus revolving the brush 20. The idlers 49 and 50 tend to keep the belts 40 and 47 in taut condition.

The conveyer belts or chains 30, 30, and 30', 30' are then revolved around the sprockets 32, 33 and 32', 33'.

The form carrying devices comprise a platform 53 upon which are two parallel series of upwardly extended revoluble form carriers 54, 54, each having an upwardly extended member 54', each carrying a fixed pinion 55 of such size and construction as to be meshable with the racks 25, 25. Positioned upon each form carrier 54 is a form 56 preferably of glass.

Experience has shown that, due to the treatments to which it is necessary to subject the forms and the platforms carrying them, wood is the most practical material from which to form the platforms, and as these are subjected to heat, steam and chemical fumes during the process of producing the final commodity, they become somewhat warped, contracted and expanded and twisted slightly away from their original shape.

It is evident, therefore, that because of this change of shape, there is a liability that the pinions 55, 55 might not mesh properly at all times with a fixed rack and hence there would be an interruption of the necessary constant and regular revolution of the forms, resulting in the production of useless articles.

I overcome this practical difficulty by employing a plurality of resiliently operated rack sections 25, 25, thus causing the rack sections to be forced into proper meshment with the pinions 55, 55, even if the platform 53 has been changed in width or otherwise, thus compensating for any difference in distance that may occur between the pinion and rack, if the latter were stationary.

The operation of the device is as follows:—

The plurality of forms 56, 56 carried by a platform 53 are repeatedly immersed in a rubber solution until a film of rubber of the proper character and thickness is deposited upon the form and the rubber dried. As the lower edge of the article is irregular in shape, it is necessary to convert it into one of regular shape and at the same time strengthen this part of the article to prevent it from tearing during use. This is accomplished by rolling the lower portion of the rubber into a bead, and as the rubber is thin and pliable and as it adheres to the form with considerable tenacity it is necessary that this

operation be performed with the greatest care.

Experience has shown that this can be accomplished by passing the revoluble forms across the face of a revolving brush, the latter being inclined with respect to the axis of a form to contact with the form from the lowest position of the rubber thereon to the height necessary for the production of a proper bead.

The revolutions of the forms and of the brush and the speed of passage of the forms across the brush surface must bear a proper relationship to each other and these movements must be maintained constant during the entire operation to prevent the production of useless articles.

The positive maintenance of these three movements by my device will be evident upon a consideration of the accompanying drawings.

A platform 53 with its rubber covered forms is placed upon the idlers 13, 13' and moved inwardly toward the device until it rests upon the carriers 31, 31' of the belts 30, 30', the links of the belts being forced into contact with the sides of the platform by means of the spring operated sprockets 35, 35', thus compensating for any inequalities of the platform and insuring a constant movement of the platform. As the platform progresses the pinions 55, 55' mesh with the teeth of the first pair of rack sections, the revolution of the chain carrying the platform forward the pinions meshing with the successive sets of rack sections, the latter because of their resiliently operative construction compensating for any inequality in the platform.

There is, therefore, a constant revolution of the forms and a constant rate of movement of the forms across the face of the inclined brushes 20, 20'.

When the lower portion of the brush abuts upon the face of the rubber the lower extremity of the latter is in the position A of Figure 7, and as the platform moves forwardly the brush produces an upwardly formed bead as indicated at B, C and D, this bead forming operation continuing until the rubber has passed beyond the upper end of the brush.

The platform then moves along the idlers 13, 13' and is removed for further operations of vulcanization and treatment.

It will thus be seen that my device presents a means whereby a constant and uniform speed of revolution may be obtained and retained between the forms and the brushes and whereby a constant and uniform speed of movement of the forms across the faces of the inclined brushes may be obtained and retained.

I do not limit myself to the particular size, shape, number, material or arrangement of parts as shown and described as these are

given simply as a means for clearly describing my invention.

What I claim is:—

1. In a bead forming device, in combination, a revoluble form, a pinion the revolution of which will revolve said form, a plurality of separate rack sections forming a continuous rack said rack sections being meshable with said pinion, resilient means forcing each rack section into meshment with said pinion, a revoluble inclined brush capable of abutment upon said form during a movement of said form, means capable of moving said form causing said pinion to mesh with each rack section during the movement of said form and means capable of revolving said brush.

2. In a bead forming device, in combination, a revoluble form carrier, a form carried by said form carrier, a pinion carried by said form carrier and revoluble therewith, a plurality of separate rack sections forming a continuous rack said rack sections being meshable with said pinion, resilient means forcing each rack section into mesh with said pinion, a revoluble inclined brush capable of abutment upon said form during a movement of said form, means capable of moving said forms causing said pinion to mesh with each rack section during the movement of said forms and means capable of revolving said brush.

3. In a bead forming device, in combination, a movable platform, a plurality of extended revoluble forms carried by said platform, pinions the revolution of which will revolve said forms, a plurality of rack sections meshable with said pinions, resilient means forcing said rack sections into meshment with said pinions, a revoluble inclined brush abutable upon said forms during a movement of said platform, causing said pinions to mesh with said rack sections revolving said pinions and means capable of revolving said brush.

4. In a bead forming device, in combination, a movable platform, a plurality of extended revoluble forms carried by said platform, a run-way within which said platform is movable, a plurality of pinions the revolution of each one of which will revolve a form, a plurality of separate rack sections forming a continuous rack carried by said runway meshable with said pinions when said platform is moved within said run-way, resilient means carried by each said rack-section causing each said rack section to mesh with said pinions when said platform is moved within said run-way, means capable of moving said platform, a revoluble inclined brush abutable upon said forms during the passage of said platform through said run-way and means capable of revolving said brush.

5. In a bead forming device, in combination, a revoluble form, a pinion the revolution

of which will revolve said form, a plurality of separate rack sections forming a continuous rack said rack sections being meshable with said pinion, resilient means forcing each 5 rack section into meshment with said pinion, a revoluble inclined brush capable of abutment upon said form during a movement of said form, means capable of moving said form causing said pinion to mesh with each 10 rack section during the movement of said form, means capable of revolving said brush, means capable of varying the height and inclination of said brush and means capable of fixing said brush in said varying positions.

15 6. In a bead forming device, in combination, a movable platform, a plurality of extended revoluble forms carried by said platform, a run-way within which said platform is movable, a plurality of pinions the revolution 20 of each one of which will revolve a form, a plurality of separate rack sections forming a continuous rack carried by said run-way meshable with said pinions when said platform is moved within said run-way, resilient 25 means carried by each said rack-section causing each said rack-section to mesh with said pinions when said platform is moved within said run-way, means capable of moving said platform, a revoluble inclined brush abutable 30 upon said forms during the passage of said platform through said run-way, means capable of revolving said brush, means capable of varying the height and inclination of said brush and means capable of fixing said brush 35 in said varying positions.

7. In a bead forming device, in combination, a movable platform, a plurality of extended revoluble forms carried by said platform, a plurality of pinions the revolution of 40 each one of which will revolve a form, a plurality of separate rack sections meshable with said pinions, resilient means forcing said rack sections into mesh with said pinions, a plurality of revoluble inclined brushes abutable 45 upon said forms during a movement of said platform, means capable of moving said platform causing said pinions to mesh with said rack sections and means capable of revolving said brush.

50 8. In a bead forming device, in combination, a revoluble form, a pinion the revolution of which will revolve said form, a plurality of separate rack sections forming a continuous rack said rack sections being meshable 55 with said pinion, resilient means forcing each rack section into mesh with said pinion, a plurality of revoluble inclined brushes capable of abutment upon said form during a movement of said forms, means capable of moving 60 said form causing said pinion to mesh with each rack section during the movement of said form and means capable of revolving said brushes.

65 9. In a bead forming device, in combination, a movable platform, a plurality of ex-

tended revoluble forms carried by said platform, a plurality of pinions the revolution of each one of which will revolve a form, a plurality of separate rack sections meshable with said pinions, resilient means forcing 70 said rack sections into mesh with said pinions, a plurality of revoluble inclined brushes abutable upon said forms during a movement of said platform, means capable of moving said platform causing said pinions to mesh with said rack sections, means capable of revolving said brush, means capable of varying the height and inclination of said brush and means capable of fixing said brush in said 75 varying positions.

10. In a bead forming device, in combination, a revoluble form, a pinion the revolution of which will revolve said form, a plurality of separate rack sections forming a continuous rack said rack sections being meshable with said pinion, resilient means forcing each 80 rack section into mesh with said pinion, a plurality of revoluble inclined brushes capable of abutment upon said form during a movement of said form, means capable of moving said form causing said pinion to mesh with each rack section during the movement of said form, means capable of revolving said brushes, means capable of varying the height and inclination of said brush and means capable of fixing said brush in said 85 varying positions.

11. In a bead forming device, in combination, a movable platform, a plurality of extended revoluble forms carried by said platform, a plurality of pinions the revolution of each one of which will revolve a form, a plurality of separate rack sections meshable with said pinions, resilient means forcing 90 said rack sections into mesh with said pinions, a plurality of revoluble inclined brushes abutable upon said forms during a movement of said platforms, means capable of moving said platform causing said pinions to mesh with said rack sections, means causing constant contact between said moving means and said platform, means capable of revolving said brushes, means capable of varying the height and inclination of said 95 brushes and means capable of fixing said brushes in said varying positions.

12. In a bead forming device, in combination, a movable platform, a plurality of extended revoluble forms carried by said platform, a plurality of pinions the revolution of each one of which will revolve a form, a plurality of separate rack sections meshable with said pinions, resilient means forcing 100 said rack sections into mesh with said pinions, a plurality of revoluble inclined brushes abutable upon said forms during a movement of said platforms, chain means capable of moving said platform causing said pinions to mesh with said rack sections, means causing constant contact between said 105

- chain means and said platform, means capable of revolving said brushes, means capable of varying the height and inclination of said brushes and means capable of fixing 5 said brushes in said varying positions.
13. In a bead forming device, in combination, a revolute form, a pinion the revolution of which will revolve said form, a plurality of separate rack sections forming 10 a continuous rack said rack sections being meshable with said pinion, means forcing each rack section into mesh with said pinion, a revolute inclined brush capable of abutment upon said form during a movement of 15 said form, means capable of moving said form causing said pinion to mesh with each rack section during the movement of said form and means capable of revolving said brush.
14. In a bead forming device, in combination, a row of revolute forms, pinions the revolution of which will revolve said forms, a rack meshable with said pinions, resilient means forcing said rack in a direction at 20 right angles toward the row of pinions into meshment with said pinions, a revolute inclined brush abutable upon said forms during a movement of said forms, means capable of moving said forms causing said pinions to mesh with said rack revolving said pinions and means capable of revolving said brush.
15. In a bead forming device, in combination, a row of revolute form carriers, forms carried by said form carriers, pinions carried by said form carriers and revolute therewith, a rack meshable with said pinions, resilient means forcing said rack in a direction at 25 right angles toward the row of pinions between said pinions and maintaining meshment between said pinions and said rack, a revolute inclined brush abutable upon said forms during their movement, means capable of moving said forms causing said pinions to mesh with said 30 rack revolving said pinions and means capable of revolving said brush.
16. In a bead forming device, in combination, a row of revolute forms, pinions the revolution of which will revolve said forms, a rack meshable with said pinions, resilient means forcing said rack in a direction at 35 right angles toward the row of pinions into meshment with said pinions, a revolute inclined brush abutable upon said forms during a movement of said forms, means capable of moving said forms causing said pinions to mesh with said rack revolving said pinions and means capable of revolving said brush.
17. In a bead forming device, in combination, a row of revolute forms, pinions the revolution of which will revolve said forms, 40 a movable rack meshable with said pinions, resilient means forcing said rack in a direction at right angles toward the row of pinions, a revolute brush abutable upon said forms during their movement, means capable of moving said forms causing said pinions to mesh with said rack revolving said pinions and means capable of revolving said brush.
18. In a bead forming device, in combination, a row of revolute forms, pinions the revolution of which will revolve said forms, a movable rack meshable with said pinions, means forcing said rack in a direction at right angles toward the row of pinions into meshment with said pinions, a revolute inclined brush abutable upon said forms during a movement of said forms, means capable of moving said forms causing said pinions to mesh with said rack revolving said pinions and means capable of revolving said brush.
19. In a bead forming device, in combination, a plurality of revolute forms, means capable of yieldingly propelling said forms and means capable of positively rotating 45 said forms during their period of propulsion.
20. In a bead forming device, in combination, a plurality of revolute forms, means capable of yieldingly propelling said forms, means capable of positively rotating said forms during their period of propulsion and means capable of interrupting said rotation when said propulsion movement is stopped.
21. In a bead forming device, in combination, a plurality of revolute forms, means capable of yieldingly propelling said forms, means capable of positively rotating said forms during their period of propulsion and an inclined revolute element abutting 50 upon said forms.
22. In a bead forming device, in combination, a plurality of revolute forms, means capable of yieldingly propelling said forms, means capable of positively rotating said forms during their period of propulsion, means capable of interrupting said rotation when said propulsion movement is stopped and an inclined revolute element abutting upon said forms.
23. In a bead forming device, in combination, a row of revolute forms, pinions the revolution of which will revolve said forms, a rack meshable with said pinions, resilient means forcing said rack in a direction at 55 right angles toward the row of pinions into meshment with said pinions, a revolute inclined brush abutable upon said forms during a movement of said forms, means capable of yieldingly propelling said forms and means capable of revolving said brush.
24. In a bead forming device, in combination, a row of revolute form carriers, forms carried by said form carriers, pinions carried by said form carriers and revolute 60

therewith, a rack meshable with said pinions, resilient means forcing said rack in a direction at right angles toward the row of pinions and maintaining meshment between said pinions and said rack, a revoluble inclined brush abutable upon said forms during their movement, yieldable means capable of moving said forms causing said pinions to mesh with said rack revolving said pinions and means capable of revolving said brush.

25. In a bead forming device, in combination, a row of revoluble forms, pinions, the revolution of which will revolve said forms, a movable rack meshable with said pinions resilient means forcing said rack in a direction at right angles toward the row of pinions, a revoluble brush abutable upon said forms during their movement, yieldable means capable of moving said forms causing said pinions to mesh with said rack revolving said pinions and means capable of revolving said brush.

Signed at New York in the county of New York and State of New York this 5
25 day of March, 1930.
